UNITED STATES PATENT OFFICE

ERNEST M. WHITE, OF LOS ANGELES, CALIFORNIA

PRESSURE INCREASING DEVICE

Application filed October 26, 1928. Serial No. 315,318.

This invention relates to pressure increasing devices and particularly to a supercharger for use with internal combustion engines, compressors, blowers, exhaust fans and in fact with any device wherein and whereby the weight or volume of fluid is to be increased over that which would normally be delivered to any of the aforesaid devices.

An object of the invention is the provision of a device which may be operated in one instance as a supercharger that is operated solely by an associated object and in accordance with operating conditions of said object.

Another object is the provision of a simple and efficient supercharger that is automatic in its operation.

The present invention is so arranged that a greater weight of air or other fluid may be delivered at all times to an associated object in accordance with the requirement.

Other objects will appear as the specification proceeds, among which objects is to increase the volumetric efficiency of any device with which the invention is associated, and with the various objects above enumerated and others, the invention consists in the novel and useful provision, formation, construction, association and relative arrangement of parts members and features, all as shown in certain embodiments in the accompanying drawings, described generally, and more particularly pointed out in the claims.

In the drawings:

Figure 1 is a side elevation of an internal combustion engine incorporating the improved invention.

Figure 2 is a side elevation of the invention associated with a pump,

Figure 3 is a cross sectional view of the invention of the form incorporated in the engine shown in Figure 1,

Figure 4 is a cross sectional view on the line 4-4 of Figure 3, and,

Figure 5 is a sectional view on the line 5-5 of Figure 3.

Referring now to the drawings, the invention as an entirety as shown in Figure 3 is designated by A, and said invention may be associated with a device B. The device B constitutes one form of air cleaner compris-

ing as it does in the present instance a casing a having a mouth end 1 within which mouth end is placed blades b. The casing is likewise provided with an outlet opening 2. Thus, if air was received within the casing, it would be given a whirling motion by the blades b and the dirt and dust would be directed against the end wall 3 of the casing and permitted to escape through the opening 2. I do not claim as any part of my invention the casing per se as any form of air cleaning device might be utilized with the invention A. The invention A may or may not be partially received within the casing.

In Figure 1, the invention A is associated with the carburetor c, which carburetor leads to the intake manifold d of the internal combustion engine C. The device A includes a compound tube e, sometimes called a draft tube, the bore of which resembles that of a pitot tube in that it has an infuser head 4 which is provided with a bell mouth leading to a constricted portion 5 with a bore of said tube tapering to provide an enlarged diameter from said zone outwardly, as shown at 6. Placed within the mouth or the infuser portion of the tube e is a nozzle or secondary infuser f and surrounding the member f is an infuser g. For convenience, the infusers will be designated as first, second and third, with the infuser 4 as No. 1, infuser f as No. 2, and infuser g as No. 3. The infuser f is provided with a conical bore which flares near the mouth thereof, as shown at 7. The infuser g is similarly constructed with the exception that it has a greater diameter than the diameter of the infuser f. The infuser f is conveniently held within the mouth portion of the infuser 4 by spaced webs 8 and webs 9 secured to the mouth of the infuser 4 hold the infuser g forward of the mouth of the infuser 4. Thus, the construction is such that there is a spacing between the periphery of the infuser g and the inner surface of the bell of the infuser 4, as shown at 10, and there is likewise a spacing between the periphery of the infuser f and the inner surface of the infuser g, as shown at 11. When the device A acts in conjunction with the air cleaner B, the periphery of the draft

tube or compound tube *e* is surrounded by a flange 12 associated with the blades *b*. Furthermore, said compound tube *e* is associated with a tube 13 leading to the carburetor *C*. The usual butterfly valve 14 may be confined within the tube 13. In Figure 2, the air cleaner is not utilized and the tube, such as 13, communicates directly with a pump *D*. This pump may be of any conventional form.

The operation, uses and advantages of the invention just described are as follows:

We assume use of the invention with an internal combustion engine. It is evident that movement of the pistons creates a vacuum in the intake manifold, which in turn induces air flow through the carburetor so that an explosive mixture may be delivered to the engine cylinders. The advantage of performing what is known as supercharging is realized in the art, and it is intended that the present invention should efficiently deliver a greater weight or volume of air to the carburetor. Furthermore, this greater weight of air is delivered at all times in accordance with requirements and operating conditions of the engine. The use of the nozzle or infuser *f* acts to induce or cause cavitation. When the device is being utilized, streams of air flow through the path or spaces 10 and 11 and through the infuser or nozzle *f*. The infuser *g* will have a jet action as the air has the most direct path through the mouth thereof and the flow of air which is induced by some member tending to draw the air through the device takes the most direct path which would be through the space 11. Thus, this flow would induce flow through the space 10. Air would likewise tend to be drawn through the infuser nozzle *f* and the rapid passage of air around the infuser nozzle would cause a zone of low pressure or cavitation at the discharge end of said infuser or roughly the zone marked 15. Thus, more air would be induced to pass through the tube *e*. It will be noted that this zone of cavitation occurs at the zone of least diameter of the tube *e* with the said tube enlarging as to diameter from said restricted zone toward the tube 13. The result is that air streams are drawn at a rapid rate through the tube *e* and the rapid expansion which occurs allows greater weight or volume of air to be passed into the internal combustion engine. There may be a vortex or whirling of the air stream as it is passed within the tube *e* due to the placement of the webs 8 and 9. In any event, a so-called squeezing action or compressive action occurs at the zone of least diameter of the tube *e*.

Quite obviously a device of this character would operate upon any type of fluid other than air.

It is important to note that this device is

adapted to be operated by some member, device or objects which is pulling the fluid through said device as distinguished from that type of apparatus wherein some injector or blower or the like is placed forward of say the infuser *g*. This device is operated solely by the associated object. The primary air stream would be that which flows through the infuser *g* as a primary air stream usually has a greater cross section. The secondary stream would be that included between the infusers *f*, *g*, and *e* or through the space 10 and the tertiary air stream would be that passed through the nozzle or infuser *f*.

Any form of displacement apparatus adapted to draw some fluid through the device *A* is contemplated by this invention.

It is obvious that various changes and modifications and variations may be made in practicing the invention in departure from the particular showing of the drawings without departing from the true spirit thereof.

I claim:

1. In a supercharger for internal combustion engines, a draft tube formed with an infuser portion, a nozzle concentric within and spaced from said infuser portion, and a second infuser in axial alignment with and in part surrounding said nozzle and in the zone of the first infuser. 90
2. In a supercharger for internal combustion engines, a draft tube, means for drawing a fluid through said draft tube, said draft tube being formed with an infuser head, a second infuser forward of the draft tube infuser head and in axial alignment therewith, and a nozzle concentrically confined between the infuser head and the second infuser. 100
3. In a supercharger for internal combustion engines, a draft tube formed with a flared mouth infuser head, a second infuser formed with a flared mouth forward of the draft tube infuser head and spaced in part from the mouth thereof, and a nozzle confined between the mouth portion of said infuser head and second infuser and spaced therefrom; said supercharger being adapted to have air drawn therethrough, the mouth portions thereof being open to the surrounding air. 105

In testimony whereof, I have signed my name to this specification at Los Angeles, California, this 7th day of August, 1928.

ERNEST M. WHITE.
